D. GUELBAUM.
 CLOSED ADJUSTABLE LIGHTING BURNER.
 APPLICATION FILED FEB. 4, 1921.

1,411,273.

Patented Apr. 4, 1922.

UNITED STATES PATENT OFFICE.

DAVID GUELBAUM, OF SYRACUSE, NEW YORK.

CLOSED ADJUSTABLE LIGHTING BURNER.

1,411,273.

Specification of Letters Patent.

Patented Apr. 4, 1922.

Application filed February 4, 1921. Serial No. 442,432.

To all whom it may concern:

Be it known that I, DAVID GUELBAUM, a citizen of the United States, and a resident of Syracuse, in the county of Onondaga and State of New York, have invented a certain new and useful Closed Adjustable Lighting Burner, of which the following is a specification.

This invention of a closed adjustable lighting burner, in its main feature of confining the gas jet and mantle within a closed housing, is similar to my patent application filed Jan. 24, 1921, Ser. No. 439,453, and has likewise for its object efficiency in the use of gas for lighting, as regards:

1. The quantity of gas consumed;
2. The quality of light obtained, and
3. The durability and strength of the incandescent materials used.

But this application differs from said pending application in the following features:

1. In place of the exact proportioning of gas and air by means of the mixing and proportioning valve, especially invented for such purposes, the proportioning of gas and air is here done approximately only, but in a simpler and cheaper way, by direct regulation of the air supply to the gas jet, prior to its entrance into the incandescent mantle.
2. In place of the usual small gas jet in the center of the incandescent mantle, the gas jet is here transformed into a cylindrical sheet stream of adjustable thickness, close to and concentric with the surrounding incandescent mantle, whereby the gas and air become thoroughly intermingled, and the whole heat developed is evenly transmitted to the mantle.

My present invention comprises the above set forth novel features, embodied in the combinations and constructions hereinafter set forth and described.

In describing this invention reference is had to the accompanying drawings, in which like characters designate the same corresponding parts in all the views.

Fig. 1 is a sectional elevation of my closed adjustable lighting burner with the annular gas and air passage into the mantle shown closed.

Fig. 2 is a similar sectional view with said gas and air passage shown fully open.

Figs. 3, 4 and 5 are horizontal sections of 55 same on the lines 3—3, 4—4 and 5—5 respectively of Fig. 1.

Figs. 6, 7, 8, and 9 are details of various parts.

The burner consists of the regulating 60 fitting 1, Fig. 1, having two inclined slots 1^a diametrically opposite each other, as shown in development on Fig. 6. This fitting is supported by the bushing 2, slidingly fitted into same, by means of the bolt 65 3, which passes through the bushing and the two inclined slots on said regulating fitting, and also through the ring 4, Figs. 1, 2 and 4, provided with the radial arms 5 serving to support a shade or reflector of 70 any style (not shown), if so desired.

The bolt 3 is provided with the two square locking washers 6 and 7 and the thumb nut 8, Figs. 1 and 4. The four edges of the washer 6 are bent up, as shown on Fig. 9: 75 two opposite edges are bent over the ring 4, butting against the regulating fitting 1, but without pressing on the ring 4, a slight clearance being left between washer and ring, as shown on the drawing; this prevents the washer 6 from turning. The other two opposite edges of the washer 6 are bent up against the surfaces of the square head of the bolt 3, thus preventing the bolt 3 from turning. 85

The edges of the washer 7 are likewise bent over the ring 4, butting against the regulating fitting 1 without pressing on the ring 4, a slight clearance being left between washer and ring, as shown on drawing, 90 Fig. 8.

Therefore, when the thumb nut 8 is tightened up, the two washers 6 and 7 will press on the regulating fitting 1, fastening it immovably to the bushing 2; while, when loosening slightly the thumb nut 8, the regulating fitting can be turned one way or the other, the bolt 3 sliding in the inclined slots 1^a shown on Fig. 6, thereby raising or lowering the regulating fitting 1 relative to the 100 bushing 2. The handle 9, sprung into position, as shown in section Fig. 3, serves as a grip for turning the regulating fitting.

In its upper part the regulating fitting 1 is provided with air openings, shown in development on Fig. 6. These openings are covered over by the ring 10, Fig. 1, having similar openings, as shown in development

on Fig. 7. The ring 10 is held on to the regulating fitting 1 by the handle or grip 11, sprung into position, as shown in section on Fig. 5. By turning the ring 10 the air inlet openings can be closed or opened as much as desired. On Figs. 5, 6 and 7 these air inlets are shown half open.

At its top the regulating fitting 1 terminates into a flange carrying the tile seat 12 having a projecting hub in the centre for supporting a mantle and which can thus be raised or lowered together with the regulating fitting, as previously explained.

In the center of the burner there is a stationary tile piece 13 with the tile pipe 14, carried on top of the metal cross piece 15, fitted securely in the bushing 2 and supported by the bolt 3, as shown on Figs. 1 and 2 and in section on Fig. 4.

These two tile pieces, 12 and 13, conform to each other in their contour, forming an annular passage between them, which can be closed or opened as much as desired by raising or lowering the regulating fitting 1 with its tile seat 12, while the tile piece 13 remains stationary on top of the bushing 2. On Fig. 1 this annular passage is shown closed, while on Fig. 2 it is shown near fully open.

The incandescent mantle 16 may be carried either by the movable tile 12, as shown on Fig. 1, in case it has resistance enough against collapsing; or it may be suspended from the top of the stationary tile pipe 14, as shown on Fig. 2.

The bushing 2 is tapped at the bottom, as shown on Fig. 1, and together with the regulating fitting 1 may be readily screwed on to any standard gas burner tip, or may be attached to any pedestal or candelabra having a gas connection.

The top flange of the regulating fitting 1 also supports the glass or porcelain globe 17, or a glass cylinder or chimney, forming the above specified closed housing around the incandescent mantle 16, to prevent its contact with outside air, as hereinafter described.

The globe is closed at its bottom by the flange of the regulating fitting 1 and its tile seat 12. Through the air openings in the upper part of the regulating fitting 1, controlled by the air-shutter ring 10, the air is admitted into the annular passage between the two tile seats 12 and 13, together with the gas flowing through the bushing 2, and intermingled with each other, pass into the interior space within the gas mantle 16, around the tile pipe 14.

The combustion gases formed by the burning of the gas within the mantle will fill up the globe and pass out into the atmosphere through the top of the globe, whose top opening is just sufficient to let these combustion gases out, but is not wide enough to let air in. Thus, the mantle is surrounded by the

hot combustion gases and has no contact with cold air.

By means of the shutter ring 10 the air inlets are opened just enough to impart to the mantle its maximum brightness, so that there will be inside the closed housing formed by the globe a minimum amount of free air, but only non-oxidizing combustion gases, in which metal fabric does not deteriorate, and, therefore such metal fabric may be used for the incandescent mantle inside that housing, as a material safe to handle and lasting indefinitely long, or, any common incandescent mantle may be used.

What I claim is:

1. A closed adjustable lighting burner, comprising a stationary bushing, a regulating fitting telescoping over said bushing and provided with regulating air inlets and a flange, a tile ring having a valve seat supported on said flange, a tile valve inside said tile ring supported on said bushing and forming with said tile ring an annular gas and air passage, a mantle around said passage and a refractory tile cylinder inside said mantle supported by said valve, means for raising and lowering said regulating fitting and adjusting said gas and air passage, a globe resting on said fitting and forming combinedly with said tile ring a closed housing preventing the contact of outside air with the mantle, and a ring with radial arms fastened to said bushing for supporting a shade or reflector, substantially as and for the purpose described.

2. A burner comprising a stationary bushing tapped or threaded at one end for connection to a gas pipe, a regulating fitting telescoping with the other end, said fitting having inclined slots on opposite sides, a ring fitting about said fitting, a bolt passing through said ring, slots and bushing, a valve supported on the bolt and locking washers on said bolt, said washers having sides bent inwardly and bearing on the fitting for securing it in any desired adjustment and sides bent outwardly and bearing against the bolt head for preventing rotation of same, said ring passing between the bent sides which bear on the fitting, and a nut for the bolt, substantially as and for the purpose specified.

3. A burner comprising a stationary bushing with a bolt passing through it, and a regulating fitting telescoping over said bushing, having opposite inclined slots sliding on said bolt and supported by same thus being raised or lowered as desired and having air inlet openings with a shutter ring and operating spring handles and provided with a flange on top for supporting a tile ring and a globe, substantially as and for the purpose set forth.

4. A burner comprising a stationary bushing, a regulating flanged fitting telescoping

over said bushing, and a tile ring carrying a gas mantle and fitting into and supported on said top flange of said fitting and having a hub on top fitting inside the gas mantle and a suitably shaped opening in the center for the gas and air passage, a tile valve inside said tile ring supported on said bushing, a tile cylinder resting on top of said tile valve, a ring with radial arms fastened to said bushing, and a globe resting on said flanged fitting, substantially as and for the purpose described.

5 5. A burner comprising a stationary bushing, a regulating fitting telescoping over said bushing, a bolt passing through the fitting and bushing, a tile ring supported on top of said fitting, and a tile valve inside of said tile ring forming together an adjustable annular passage for the gas and air mixture and supported by a cross piece 10 mounted on the bolt and provided with a projection on top supporting a tile cylinder, substantially as and for the purpose specified.

15 6. A burner comprising a stationary bushing, a fitting telescoping over said bushing, a tile ring seated inside said fitting, a tile valve fitting inside said tile ring and supported by said bushing, a cylinder supported on said valve, and a mantle made of wire 20 fabric supported on the hub of said tile ring with an annular space between said cylinder and mantle for the passage of the com-

bustion mixture of gas and air, substantially as and for the purpose set forth.

7. A burner comprising a bushing, a fitting telescoping over said bushing, a tile ring seated inside said fitting, a tile valve fitting inside said tile ring, a mantle supported on said tile ring, and a closed housing around said mantle formed by a globe 35 supported on the flange of said fitting and having a contracted opening on top preventing outside air from getting in contact with said mantle, substantially as and for the purpose described.

40 8. A burner comprising a bushing, a fitting telescoping over said bushing, a bolt with double locking washers passing through said bushing and fitting, a tile ring seated inside said fitting, a tile valve fitting 45 inside said tile ring, a mantle supported on said tile ring, a closed housing around said mantle supported on said fitting, and a ring around said fitting with the bolt of said bushing and fitting passing through it and 50 serving as a clamp for the locking washers of said bolt to prevent their turning and also provided with radial arms for supporting a shade, substantially as and for the purpose specified.

55 In testimony whereof, I have hereunto signed my name, at Syracuse, in the county of Onondaga, and State of New York, this 2nd day of February, 1921.

60 DAVID GUELBAUM.
